COMBINED FILE AND DISPLAY RACK

Sven-Eric Juhlin, Gustavsberg, Sweden, assignor to AB
Gustavsbergs Fabriker, Gustavsberg, Sweden

Filed Dec. 24, 1974, Ser. No. 536,170

Claims priority, application Sweden July 11, 1974

Term of patent 14 years

Int. Cl. D20—02

U.S. Cl. D6—24

The figure is a perspective view of a combined file and display rack.

All four sides of the stand are identical as seen in elevation.

The undersides of the base and of the superposed trays are plain.

I claim:

The ornamental design for a combined file and display rack, as shown and described.
